UNITED STATES PATENT OFFICE

PETER J. SHEUM, OF MONACA HEIGHTS, PENNSYLVANIA, ASSIGNOR TO PITTSBURGH SCREW AND BOLT CORPORATION, A CORPORATION OF PENNSYLVANIA

THREAD PROTECTOR

Application filed January 20, 1928. Serial No. 248,128.

This invention relates to thread protectors and more particularly to an improvement in the construction thereof.

In my application for thread protectors 5 executed by me under date of November 8, 1927, issued as Patent No. 1,762,248, June 10, 1930, I disclosed a thread protector that is similar in some respects to the present protector, but unlike the present protector in 10 many desirable features.

The protector disclosed in my above mentioned application is provided with a plurality of threaded openings in the body of the protector having threaded studs disposed 15 therein and a copper strip fixed to the body of the protector and adapted to lie across the threaded openings to prevent the studs from coming in contact with the threads to be protected. The present protector is provided 20 with an improved means which is more desirable for certain applications and while this improved means embodies threaded openings and threaded studs, it is different from the above in that copper points are provided on 25 the threaded studs for contacting with the threads to be protected instead of the copper strips and in addition, that portion of the body surrounding the threaded opening is expanded outwardly or inwardly as the case 30 may be so that the threaded studs may be removed from contact with the threads and still extend through the body of the protector. In this way the additional care that is required to withdraw the threaded studs only 35 a certain distance in order that they may remain in the threaded openings, as disclosed in my above application, is eliminated.

Another advantage of the present protector for certain applications is the elimination 40 of the expanded end. The present protector is cheaper to manufacture in view of the elimination of the expanded end and the substitution therefore of an outwardly or inwardly extending flange as the case may be for protecting the end of the pipe. The flange being outwardly extended when the protector is adapted for use with internal threads and inwardly extended when adapted for use with 45 external threads.

50 An object of this invention is to provide

a thread protector for the internal or external threads on the end of a pipe that is simple in structure and inexpensive to manufacture.

Other objects lie in the novel construction and combination of parts that will herein- 55 after be described and illustrated in the accompanying drawings, wherein,

Fig. 1 is a sectional view of a protector embodying the invention disposed on the end of a pipe having external threads, 60

Fig. 2 is a view taken along the line II—II of Fig. 1,

Fig. 3 is a sectional view similar to Fig. 1 showing a protector embodying the invention disposed on the end of a pipe having 65 internal threads, and

Fig. 4 is a sectional view taken along the line IV—IV of Fig. 3.

In the drawings, Figs. 1 and 2 illustrate a 70 protector for protecting the threads on the end of a pipe or device 11 having external threads 12. The protector comprises a cylindrical body portion 13 having its outer end terminating in an inwardly extending annular flange 14. The flange 14 lies in a plane 75 substantially at right angles to the longitudinal axis of the cylindrical portion 13 and is adapted to engage and protect the outer end of the pipe 11.

The cylindrical portion 13 of the protector 80 is provided with a plurality of semi-spherical projections 15 each having a threaded opening 16 therein. The threaded openings 16 are provided with threaded studs 17 having copper points 18, or points of some mate- 85 rial softer than the threads to be protected.

The advantage of the semi-spherical pro- 90 jections 15 containing the threaded openings 16, over my protector disclosed in the above mentioned application, is that the threaded studs 17 may be released from contact with the pipe threads and still be entirely through the cylindrical wall 13. This is accomplished by means of the semi-spherical projections 95 which provide a space 21 between the inner walls of the protector and the threads to be protected. In providing the threaded studs with copper points, the necessity of the copper strip is eliminated, making the present protector less expensive to manufacture. 100

Figs. 3 and 4 illustrate the present protector as applied to the end of a pipe 11 having internal threads 12. In this case the cylindrical portion 13 of the protector has an external diameter substantially the same as the internal diameter of the threads to be protected and of course the annular flange 14 extends in an outward direction instead of inward, as in the protectors illustrated by Fig. 1 and also the semi-spherical projections 15 extend inwardly instead of outwardly as does the projections 15, illustrated in Fig. 1.

While I have illustrated and described this invention in connection with a pipe having external or internal threads, it will be obvious to those skilled in the art that the protector is equally adapted to protecting the plain ends of pipes or the like.

What I claim as new and desire to secure Letters Patent on, is:

- 20 1. In a protector of the type adapted to slide over threads to be protected, a tubular body having a pipe end protecting right angled flange at one end thereof with portions of the body metal intermediate the ends of the protector pressed out of the plane of the body, and members threaded through said pressed out portions and provided with relatively soft contact ends for engaging the thing to be protected.
- 25 2. In a thread protector of the type adapted to slide over the threads to be protected, a generally tubular body having a pipe end protecting right angled flange at one end thereof, the body at points intermediate its ends being forced out of the body plane to form clamp supports, and clamping screws threaded through said supports and having relatively soft metal contact ends for engaging the threads to be protected.
- 30 3. In a thread protector, a generally tubular body slidable over the threads to be protected having a projecting pipe end protecting flange at one end thereof, a series of bulging portions at about the longitudinal center of the body and soft ended screws threaded through said bulging portions for engagement with the threads to be protected.

In testimony whereof, I have hereunto subscribed my name this 31st day of December, 1927.

PETER J. SHRUM.
